UNITED STATES PATENT OFFICE.

ENGELBERT L. JAWOREK, OF HOQUIAM, WASHINGTON.

EMBROIDERY-HOOP HOLDER.

Application filed March 29, 1923. Serial No. 628,560.

To all whom it may concern:

Be it known that I, ENGELBERT L. JAWOREK, a citizen of the United States, residing at Hoquiam, in the county of Grays Harbor and State of Washington, have invented certain new and useful Improvements in an Embroidery-Hoop Holder, of which the following is a specification.

My invention relates to an embroidery hoop holder and has for its principal object to provide novel means for holding a hoop or circular frame upon a suitable support whereby the piece of work held by the hoop or frame can be easily worked upon with both hands if desired.

Another object of the invention is to provide a device of this nature which will be simple, cheap, durable, and effective.

Another object of the invention is to provide a support including means for holding the embroidery hoop or frame in different positions in relation thereto.

With the above and numerous other objects in view as will appear as the description progresses, the invention resides in certain novel features of construction, and in the combination and arrangement of parts as will be hereinafter more fully described and claimed.

In the drawing

Figure 1 is a side elevation of the device embodying my invention a portion of the clamp being shown in section.

Figure 2 is a plan view of the frame,

Figure 3 is a perspective of the standard or peg, and

Figure 4 is a detail section taken through the frame substantially on the line 4—4 of Figure 2, also showing the peg positioned in relation thereto.

Referring to the drawing in detail it will be seen that my invention consists generally of an embroidery frame A supported on a standard B which in turn is supported by a clamp member C. The frame A consists of the outer hoop 1 and inner hoop 2. The inner hoop 2 is provided with a way 3 formed by the arcuate shaped member 4 having feet 5 at its terminals which are suitably attached to the inner hoop 2. The concaved face of the arcuate member 4 faces the inside of the hoop 2.

The standard B is in the form of a wedge shaped peg and the upper or larger end thereof is provided with a block 6 having 55 arcuate sides so as to fit snugly within the way 3.

The clamp member C includes a body 7 having an upper bar 8 extending transversely therefrom for engagement with the 60 upper face of a support such as a table, and a lower bar 9 extending transversely from the lower end thereof adapted to be disposed below the support on the table. In this lower bar 9 there is disposed a clamp screw 65 10 having a plate 11 for engagement with the lower surface of the support or table. The upper end of the body 7 is provided with a downwardly tapered opening 12 for receiving the lower end of the standard B. 70 It will thus be seen that the frame A may be rotated to extend in any desirable relation to the support to which the clamp C is attached and with a little pressure upon the standard B will be locked in the desired 75 position because of the wedge shaped formation of this standard and the opening 12.

Although I have described my invention with a certain degree of particularity it is to be understood that numerous changes in 80 the details of construction and in the combination and arrangement of parts may be resorted to without departing from the spirit of the invention as hereinafter claimed.

Having thus described my invention what 85 I claim as new is:—

In combination, a clamp, a standard rising from the clamp, a block disposed on the upper end of the standard, the thickness of said block being less than that of the standard so as to provide a shoulder at the junction of the block with the standard, and an embroidery frame adapted to rest on the shoulder and including an outer hoop and an inner hoop, an arcuate shaped member 90 95 having feet at its ends attached to the inner face of the inner hoop thus forming a way to receive the block.

In testimony whereof I affix my signature in presence of two witnesses.

ENGELBERT L. JAWOREK.
